[57] ABSTRACT

A welt forming machine has been provided which is a combination comprising: a sewing machine including a looper, a needle bar and a stop motion means for a

sewing machine needle bar; feed means for feeding work piece for said sewing machine including means for varying the rate of feeding of said feed means independently of a rate of sewing, said feed means feedingly urging a work piece transversely to said sewing machine between a first feed and a second feed position; means for clamping a work piece onto said feed means and operatively interconnected with said feed means; means for holding a welt-defining work piece operatively interconnected with said feed means and said means for clamping, said holding means transversely depending from said sewing machine; means for folding said welt-defining work piece operatively interconnected with said feed means and said clamping means and articulately interconnected with said clamping means; means for center cutting said work pieces operatively interconnected with said sewing machine and said feed means between said first and second feed position; means for engaging said stop motion means; means for engaging an upper thread of said sewing machine upon completion of sewing of said work pieces; means for cutting said upper thread operatively interconnected with said means for engaging said upper thread; means for indexing said feed means; means for end cutting said work pieces operatively interconnected with said means for indexing said feed means; and means for returning said feed means to said first feed position—by means of the above combination, weltings such as encountered in pants back pockets, button holes, etc. are produced.

FIG. 19

POCKET WELTING MACHINE

This invention pertains to a welting machine; more particularly, this invention pertains to a novel machine by which welting of a pants back pocket or similar garment opening welting is achieved.

THE PRIOR ART

In the art of welting garment openings such as pocket openings and button holes, the commonly employed machine has been the Reece Pocket Welting Machine described in U.S. Pat. Nos. 2,555,095; 2,529,072; 2,573,359, and 2,604,062. An improvement in the method of controlling this prior art machine has also been disclosed in U.S. Pat. No. 3,572,266 to Rodney W. Champney. However, the various improvements which have been sought as means to overcome the limitations of the Reece Pocket Welting Machine have, for the most part, involved merely modifications in the circuitry or component parts or modifications in the mode of operation of the prior art machine.

BRIEF DESCRIPTION OF THE INVENTION

According to the present invention, a machine for welting a back pocket on pants or button holes has been discovered which represents an improvement over the prior art machines and methods such as illustrated in the above-mentioned patents. The present machine achieves the welting operation not only in a simpler manner but also with considerably fewer elements in the sewing machine-welting machine combination. Moreover, means for controlling the present machine, in combination with machine elements, are simpler and represent a considerable improvement over the prior art means. References herein are made to copending companion applications Ser. No. 128,831, filed Mar. 29, 1971, and Ser. No. 157,842, filed June 29, 1971, which disclose a needle bar stop motion device employed with this machine; the stop motion or the needle bar positioning device which has been disclosed in the afore-mentioned applications finds a number of uses outside the combination herein. In respect to the feed section further described herein, a companion application Ser. No. 195,240, filed Nov. 3, 1971, now U.S. Pat. No. 3,736,894, discloses feed means employed herein which also find use outside the combination herein. Pertinent parts of the needle bar stop motion device and the feed means will be described herein in more detail and will provide for a complete understanding of the present invention.

With reference to the previously mentioned U.S. Pat. No. 3,572,266, in this patent there has been disclosed the work piece used in the production of a welted back pocket opening, the sequence of operations performed on the work pieces, and how the work sequence is accomplished in a Reece pocket sewing machine.

As the finished product is the same during the work sequence when made by the prior art devices or by the present device, the description of the work piece will be based on the last-mentioned patent. Obviously, reference can be made to this or the other mentioned patents which describe the work piece production cycle.

DESCRIPTION OF THE INVENTION

For a more complete description of the invention and in reference to Figures wherein:

FIG. 1 illustrates a perspective view of the novel welting machine;

FIG. 2 shows a side view the welting machine depicted in FIG. 1;

FIG. 3 shows in partial top view the movable work feed plate shown in FIGS. 1 and 2;

FIG. 4 illustrates in partial cross-section the work feed plate depicted in FIG. 3 and the means for indexing the work feed plate for positioning the same over the end cut knives;

FIG. 5 illustrates in a front view the head of the sewing machine shown in FIG. 1, including the presser foot thereof;

FIG. 6 illustrates, in cross-section, the presser foot block shown in FIG. 5, including the thread pick-up fingers and means for operating the same;

FIG. 7 illustrates the interconnecting lever means between the center cut knives and the work feed plate;

FIG. 8 illustrates a lever action of the lever shown in FIG. 7 as cammingly operating the center cut knife;

FIG. 9 is a side elevational view, partly in section, illustrating the configuration of the transmission system of the present invention during reciprocation of the needle bar;

FIG. 10 is a side elevational view, similar to FIG. 9, illustrating the configuration of the transmission system when the needle bar is held in its raised position;

FIG. 11 is an exploded perspective view of the components of the device in the configuration illustrated in FIG. 9;

FIG. 12 is an exploded perspective view of the components of the device when in the configuration of FIG. 10;

FIG. 13 is a schematic illustration of the resultant stitch pattern produced by the work feed plate and speed regulator of the present invention;

FIG. 14 is a schematic side view of one embodiment of the work feed plate and speed regulator of the present invention, in the first position of the plunger;

FIG. 15 is a schematic view similar to FIG. 14 of another embodiment of the present invention illustrating the position of the plunger after the initiation of movement of the work feed plate from its first to its second position;

FIG. 16 is a schematic illustration similar to FIG. 15 illustrating the configuration of the plunger just prior to the work feed plate and plunger achieving their respective second positions;

FIG. 17 is an illustration of the configuration of the plunger with respect to the cylinder at the second position of the plunger and the work feed plate; and

FIG. 18 illustrates a fluidic logic control means employed in conjunction with back pressure, machine-element sensors for controlling and operating the machine depicted in FIG. 1;

FIG. 19 illustrates another fluidic logic control means employed in conjunction with back pressure, machine-element and sewing operation sensors for controlling and operating the machine depicted in FIG. 1.

In reference to FIG. 1 and a brief description of the particular component parts of the present device, the welting machine 5 is placed on a stand 10 and consists of work feed plate 11 which rides on rails 12; the rails 12 are rigidly affixed to the sewing machine 14. A presser foot 16 is placed longitudinally along the axis of the work feed plate and perpendicularly against the head of the sewing machine 14. The presser foot 16

contains a center cut knife section designated as 17 as it is used for pocket welting. A needle bar 87 has attached thereto two needles 65, only one of which is shown in the Figures. A sewing machine base 19 to which the rails 12 are rigidly affixed rests on channel members 18 rigidly affixed to the stand 10.

The upper thread holders (not shown) are each holding a spool (not shown) for each of the needles 65; the thread holders have corresponding thread tensioners and thread guides attached thereto as is common in the Reece sewing machine for the upper thread tension control means. These means will not be described in any detail as a reference can be readily made to the previously mentioned patents for the understanding and functioning of these means or to other patents in the sewing machine arts.

Underneath the work feed plate 11 and slightly left of the sewing machine is placed the end knife section 26. On top of the work feed plate 11 are placed a pair of clamps 27 as well as a pair of folder arms 56. The feed control section has been indicated as 20.

Attached directly to the sewing machine 14 is the sewing machine motor 37 (not shown in FIG. 1, shown in FIG. 10). It may also be attached to the stand 10 by appropriate means, and the sewing machine 14 may be driven by a belt. At the other end of the stand 10 and protruding upwardly are two spacers 36 which hold the rails 12. Rails 12 have been rigidly affixed to the sewing machine base 19 as well. Suitable pneumatic fluid source used for the various control cylinders or pistons associated with this machine is introduced by means of a conduit 39 (not shown). A master power switch 40 (not shown) has also been provided. Similarly, a foot pedal 41 (not shown but described in conjunction with FIG. 18) which the operator activates is conveniently placed at the sewing machine end of the stand. When operating the machine, an operator sits at the machine facing the right side of the machine and at the end of rails 12.

Work feed plate 11 rides in the rails 12 and is positioned in grooves 47 by appropriate roller bearings 48 (of sufficient number) as shown in FIG. 7 which are attached to work feed plate 11 and ride protrudingly in grooves 47. On the top of the work feed plate 11 are placed the above-mentioned clamps 27 attached to a clamp pivot post 49 conveniently spaced apart by clamp spacer 61. Clamps 27 are being lifted upwardly or urged downwardly by a double acting cylinder 51 which pivots on cylinder pivot plate 54 which plate is positioned between clamp lift posts 50 via an appropriate shaft 53. Clamps 27 are attached to clamp lift plate 52 which in turn is attached to the cylinder 51. A pair of folder arms 56 are placed interiorly to the clamps 27. These folder arms 56 are placed on the transverse folder arm rest plate 59 and are articulated by cylinders 57 (not shown in FIG. 1, shown in FIGS. 2 and 3) affixed rigidly to cylinder mounting posts 60, each of which is attached to one of the clamp arms 27. Thus the folder arms 56 move inwardly and outwardly when activated by cylinders 57 and upwardly and downwardly with clamps 27 when activated by cylinder 51. The folder arms 56 urge a welting patch into a folded position about presser foot 16 with springs 56a (shown in FIG. 3) when the feeder plate 11 is in its forwardmost position, as described hereinafter. A folder arm back pressure pneumatic sensor 58 and 58a placed in sensor

block 58b on rest plate 49b senses the in and out positions, respectively, of the folder arms.

The sensing of machine elements by means of a pneumatic back pressure has been described in application Ser. No. 44,772, filed June 9, 1970, in the name of L. William Breck, Jr., and assigned to the same assignee as the present application and incorporated by reference herein.

As an optional item, at the outer edge of work feed plate 11 is a spring-like pocket clamp 21, activated by pocket clamp cylinder 22. When cylinder 11 extends the spring pocket clamp 21 and positions thereby clamp shank 21a in the slim part of the spring 21b under clamp holder 24, a pocket having been placed on work feed plate 11 is thereby removably engaged with work feed plate 11 and the outer garment component, i.e., a pant leg then placed over the pocket and under clamps 27.

The presser foot which has been previously identified as 16 is an inverted T-shaped device which has a center knife slot 62 extending into the vertical section of the T in which the center cut knife 63 fits. Needles 65, one each on each side of the center knife slot 62, in turn are positioned in needle apertures 64 in the presser foot 16. The presser foot 16 in turn is attached to the sewing machine head 14 via presser foot block 68 to post 66 and activated upwardly and downwardly by presser foot cylinder 67 and urged downwardly and upwardly by guide rods 69 which are attached to presser foot 16 and which rods slide in presser foot post 66. Cylinder 67 is fixedly attached to post 66, and its rod 67a is attached to block 68.

An appropriate back pressure sensor 70 mounted on one of the guide rods 69 signals the down position of the presser foot when the back pressure sensor post 70a closes the back pressure sensor port opening 70b; the two positions are indicated by the phantom lines in FIG. 5.

The presser foot block 68, in two recessed channels 73, as shown in FIGS. 1, 5 and 6, carries a reciprocally activatable rectangular frame 76 to which frame is attached at the sewing machine end thereof a hook-ended thread pick-up finger 72, one each for each needle 65; the thread pick-up fingers are placed in a thread pick-up finger block 74. A pneumatic piston 77 placed interiorly in said presser foot block 68 upon conclusion of the sewing operation moves forwardly and engages threads 78 with pick-up fingers 72 from each of the needles and holds these back so that these may be cut by moving the same against knives 78a, one each for each of the needles such as when the work feed plate 11 is indexed in its next position for operating the end knives. The piston 77 has been indicated in cross-section in the presser foot block 68 in FIG. 6, including the pneumatic fluid port 77a, the spring 77b, and rod 77c which is attached to block 74.

The center cut knife 63 is activated by a knife cam 79. The mechanism for positioning the knife 63 is different from the Reece pocket welting machine and is illustrated in FIGS. 7 and 9 herein. Thus, the knife cam post 80 is pendant from the sewing machine and has attached thereto a knife cam pivot point 81; further, the knife cam 79 has a stud 79a protruding into an eye 85a of a knife cam lever 85 attached to the side of the sewing machine 14. Lever 85 is urged upwardly by means of spring 84. At the lower end of lever 85 there is mounted a cam follower roller bearing 84a which fol-

lows at the underside of work feed plate 11 a cam land 84b. This cam land is equivalent to a slope of three-sixteenth inch of rise for 3 inches of travel for work feed plate 11.

The needle bar 87 carrying two needles 65 has the knife pivot point 89 and a knife spring 90 housed therein. As the work feed plate 11 travels, the cam follower roller bearing 84a causes the lever 85 to be moved upwardly and hence knife cam 79 rearwardly.

The feed section previously identified as 20 and in the preferred mode shown in FIG. 4 is placed under the work feed plate 11 and further consists of an index cylinder 96 which by means of the index cylinder rods 97 and index cylinder rod connecting block 99 is attached to the work feed plate 11 at index cylinder pivot point 100. The index cylinder is employed for proper positioning of the work piece for making an end cut with end knives 134. When indexed by cylinder 96, work feed plate 11 rides in the side rails 12. Index cylinder 96 is slightly pivotable on the guide pivot plate universal bearing 100a.

In FIGS. 2 and 3, an alternative work feed plate indexing is illustrated. Instead of pulling work feed plate 11 as in FIG. 4, index cylinder 96 pushes the work feed plate. The index cylinder 96 and the index cylinder rod 97 are placed under work feed plate 11 as shown in FIG. 3; but two connecting rods 96a; one on each side of cylinder 96, transmit the force from control link 422 via point 424 which is connected with a flexible connection strip 96b to connecting rods 96a. The flexible connection strips 96b, one of each of the rods, accommodate the arcuate travel of control link 422. Index cylinder rod 97 is then attached to work feed plate 11 by means of angle section 97a.

The "work feed plate back" machine element back pressure sensor is identified in FIG. 4 and 105 and placed so as to signal the completion of indexing, i.e., when cylinder 96 places the work feed plate in position for the end knife section 26 to become operative.

In respect to the feed section 20 as it is associated with the sewing sequence, a "stop sew" pneumatic back pressure sensor is positioned on feed link 422 and designated as 106 (shown in FIG. 2).

The end knife section 26 consists of end knife section plate 124 placed on the stand 10. Projecting from plate 124 upwardly are end knife posts 126 on top of which is placed bar 125; on the last also rests bracket 127 carrying the two end knives 134. The bracket 127 is urged upwardly by cylinder 127a. Bar 125 has three apertures through two of which are inserted guide rods 130, which are fixedly attached to knife bracket 127 and which allows the knife bracket 127 to ride properly upwardly to make the appropriate end slits which are necessary for inverting the welting path, as is well known in the pocket welting art. The pair of knives 134 are inferiorly facing T sections. An end knife up 139 and down 139a pneumatic back pressure sensors and their closure block 137 is placed on shaft 130 and signifies the up and down position of the end knife bracket 126 and thus the end knives 134. The up and down pneumatic back pressure sensors 139 and 139a, respectively, and the blocks 137 are illustrated in FIG. 2 wherein the guide rod 130 and block 137 are shown the "down" position. The block 137 has on each upper and lower surface an elastomeric cover which completes the pneumatic back pressure sensor circuit.

An appropriate means, such as a cut-out section 133, has been provided in the work feed plate 11 which provides for the throat plate 135 and throat plate bracket 135a as well as provides the necessary aperture for the end knives 134 to project upwardly.

After the sewing, indexing and end cutting operations have been completed, the clamp arms 27 are raised, and an appropriate ejection device (not shown) is then used to eject the work piece. An illustrative ejection device is an air blast provided by a pneumatic fluid source and an appropriately interposed and activated valve.

The sewing machine and stop motion device will now be described herein and in reference to the previously 15 mentioned copending applications Ser. Nos. 128,831 and 157,842.

Referring now to the drawing in detail and initially to FIG. 9 thereof, it will be seen that a sewing machine 210 embodied in the present pocket welting machine 20 has a housing 212 which includes a rotary electric motor 37 that provides the power in the sewing machine to reciprocate a needle bar 87 during the sewing operation through a transmission system 218.

Motor 37 includes a drive element 220 rigidly secured to the shaft 222 of the motor, which drive element is operatively connected to the transmission system 218 to supply rotary motion of element 220 to reciprocating motion for moving needle bar 87 between extreme upper and lower positions with respect to a looper 292 mounted in housing 212 for cooperation with the needle 65 mounted in the needle bar 87.

Transmission system 218 also includes a crank arm 288 pivotally connected at one end by a pivot pin 230 to rotating element 220. The other end of crank 288 is pivotally connected by pivot pin 232 to one end of an idler link or pitman 234. The latter is utilized to transmit motion from motor 37 to oscillate the lever 236 that drives the needle bar 87. The end 238 of lever 236 is pivotally connected at 240 to pitman 234, and when the pitman is in the configuration illustrated in FIG. 9, wherein its line of thrust is substantially perpendicular to the lever, rotation of motor 37 causes reciprocation of pitman 234 and thus oscillation of lever 236. The end 244 of lever bar 236 is pivotally connected through an intermediate link 246 to needle bar 87 in order to provide a smooth reciprocating motion of the needle bar during rotation of motor 37 and oscillation of lever 236.

In order to maintain the line of thrust of pitman 234 substantially perpendicular to lever 236 during reciprocation of the needle bar 87, a control linkage 250 is included in transmission system 218, which linkage is also utilized to stop the reciprocation of the needle bar 87 when desired. Control linkage 250 includes a lever 252 pivotally mounted in housing 212 by pivot pin 254. The end 256 of lever 252 is pivotally connected to the actuator rod 258 of a hydraulic or pneumatic double acting cylinder or ram 260 pivotally mounted in housing 212 via attachment at 262. By selectively actuating cylinder 260, lever 252 may be moved between first and second positions in order to vary the location of the line of thrust of pitman 234 from the position shown in FIG. 9 wherein the line of thrust is substantially perpendicular to lever 236; and the position illustrated in FIG. 10 wherein the line of thrust of the pitman is in substantial alignment with the lever so that the motion of the

crank arm 228 is not transmitted to lever 236 and pitman 234 merely idles about its pivotal connection 240 with the lever. This is accomplished by the utilization of a control link 264 which is pivotally connected at 266 to the end 268 of lever 252 and also is pivotally connected at its opposed end to pivot pin 232 with crank arm 228 and pitman 234.

As illustrated in FIG. 9 when the actuator rod 258 of cylinder 260 is extended, control link 264 cooperates with lever 252 to hold pitman 234 and thus its line of thrust substantially perpendicular to the lever 236. That is, as illustrated in dotted lines in the drawings, as the pivot point 230 of crank 228 moves along its circular path because of its connection with rotary element 220, the pivot point 232 and thus pitman 234 are held by link 264 below pivotal connection 240 and lever 236 so that the up and down movement of pivotal connection 232 is transmitted to lever 236 and causes reciprocation of needle bar 87 with respect to looper 292. A stop 270 on housing 212 limits the extent of movement of lever 252 and control rod 258 under the influence of the double acting cylinder 260; when in the position illustrated in FIG. 9, it is positioned to properly locate lever 252 and control link 264 for proper and efficient operation of the device.

Pitman 234 is provided with an extension 272 integral therewith which is utilized to oscillate the looper 292 in timed relation with the up and down motion of needle bar 87 for proper cooperation with needle 65. Extension 272 is pivotally connected at 274 to a transmission link 276 which is pivotally connected at 278 to a crank arm 280. The latter is pivotally mounted in housing 212 at 282 and has a bevel gear 284 formed integrally therewith. Gear 284 is meshed with a corresponding bevel gear 286 which is secured to the end of a transmission shaft 288 mounted in housing 212 by a conventional mounting system (not shown). The end 290 of shaft 288 is secured to a looper 292 of conventional construction. By this arrangement, it is seen that as pitman 234 is reciprocated between its upper and lower positions, as illustrated in solid and dotted lines in FIG. 9, the pivot points 274 and 278 will be similarly reciprocated and crank arm 280 will be oscillated. The oscillation of the crank arm is transmitted by bevel gear 284 to gear 286 to effect oscillation of the transmission shaft 288 and thus looper 292.

When it is desired to stop reciprocation of needle bar 87, the actuator rod 258 of ram 260 is retracted, thereby moving lever 252 to the position illustrated in FIG. 10. As a result of this motion, the control link 264 moves pivot point 232 between crank arm 228 and pitman 234 out from beneath lever 236 so that the pitman and thus its line of thrust are in substantial alignment with lever 236. Accordingly, as element 220 continues to rotate under the influence of motor 37, the idler arm 234 (also called pitman) merely idles about pivot point 240 (substantially between the limits illustrated in solid and dotted lines in the drawing) so that needle bar 87 is not reciprocated. Since the thrust provided by pitman 234 is directed substantially longitudinally along lever 236, the lever is not oscillated. However, as pitman 234 continues to oscillate within the limits illustrated in the drawing, the extension 272 thereof also continues to oscillate and moves upwardly and downwardly with respect to pivot point 240 along a small arc. This small oscillation is transmitted through connecting rod 276 to crank 280 to effect a slight oscillation

of transmission bar 288 and looper 292. The continued oscillation of looper 292 is advantageous in that the looper can cooperate with the fixed knife blade 78a shown in FIG. 5 to cut the thread on completion of the sewing operation.

When the lever 252 is moved in this manner from its first to its second position, the control link 264 is positioned in parallel to that portion of the pitman 234 between pivot points 240 and 232, with the pivotal connection 266 in alignment with pivot point 240. This is permitted because the various links and levers are dimensioned so that control link 264 has a length between pivot points 232 and 266 corresponding to the distance between pivot points 232 and 240 of pitman 234. Since the location of pivot point 266 is fixed because of its connection to the rigid lever 258, when it moves into the configuration wherein links 264 and 234 are in parallel relation, pivot point 240 becomes fixed so that the lever arm 236 is locked in position and is prevented from oscillating.

As thus far described, the mechanism of the illustrative embodiment of the sewing machine 14 used with the present invention is utilized for reciprocating the needle bar 87 over a fixed distance or amplitude and for stopping reciprocation thereof when desired. Two needles 65 may be carried by bar 87. It is noted, however, that the control system 250 may also be used to control or vary the amplitude of oscillation of the needle bar 87.

To control the amplitude of reciprocation of reciprocating element, ram 260 may be provided with a conventional control device (not shown) by which the amount of retraction of actuator rod 258 may be controlled and varied. Thus, when rod 258 is fully extended, as in FIG. 9, the reciprocating member, needle 65 in the illustrative embodiment, is reciprocated at the maximum possible amplitude, i.e., it moves the maximum possible distance between its upper and lower limits. As the rod is retracted and before it is fully retracted as in FIG. 10, the pivot points 240 and 266 are moved towards each other with a scissors-like motion between members 264, 268, 236 and 234. As a result, the amplitude of oscillation of pivot point 240 and thus bar 216 is decreased. By stopping retraction of rod 258 at any point between the extremes illustrated in FIGS. 9 and 10, a desired amplitude of oscillation of needle bar 87 may be selected.

The stop motion control mechanism 250 also can be utilized to stop the reciprocating motion of needle bar 87 at any position of crank arm 228. When the stop motion mechanism is operated, the linkage is moved from the positions illustrated in FIG. 9 to the position illustrated in FIG. 10, and the needle bar 87 is held in its raised position. However, it is preferable that the needle bar be stopped or disengaged from the material on which it is working only after the needle 65 has passed its lower most position with respect to the looper 292 so that the looper is engaged with the thread supplied by the needle. By this arrangement the looper holds the loop below the cloth so that when the stitch is cut, it will not ravel back, as would possibly be the case where the motion is stopped at a position wherein the looper is withdrawn from the loop. Accordingly, a gating system 300 is provided to insure that the stop motion actuating mechanism 250 will stop reciprocation of the needle bar 87 only after the needle 65 has moved to its lowermost position.

Gating mechanism 300 includes a gate or cam member 302 having a leading cam edge 304. Gate 302 is formed integrally with a quadrant gear 306 that is pivotally mounted in housing 212 by pivot pin 308. The gate 302 and gear 306 are positioned to be forwardly of links 234, 252 and crank 228, as illustrated in FIGS. 10, 11 and 12. However, for the sake of clarity, the gate has been broken away in FIG. 9. Quadrant gear 306 is meshed with a second quadrant gear 310 which is formed integrally with lever 252. In the first position of lever 252, illustrated in FIG. 9, the gate 302 and its cam surface 304 are positioned out of the path of travel of the pivotal connection 232 between pitman 234 and crank arm 228. However, when actuator rod 258 is retracted to move lever 252 into the position illustrated in FIG. 10 to stop reciprocation of needle bar 87, the gate 302 and its cam edge 304 are moved into the position illustrated in FIG. 10 wherein the edge 304 is positioned in the path of travel of pivot point 232.

A cam follower 312 (see FIGS. 11 and 12) is located at pivot point 232, and is biased outwardly by a spring 314. Follower 312 is adapted to engage edge 304 during rotation of crank arm 228 prior to stopping reciprocation of needle bar 87. Thus, referring to FIG. 9, as actuator bar 258 is retracted and cam surface 304 is moved into the position illustrated in FIG. 10, if crank arm 228 and the pivotal connection 232 are moving upwardly on the right side of motor 37, cam follower 312 would engage edge 304 and hold pivot point 232 and pitman 234 below point 240 so that the line of thrust of the pitman is still effective to oscillate lever 236 and lower needle bar 87. As the pivotal connection 230 of crank arm 228 with element 220 passes the top portion of its path of travel—that is, the 12 o'clock position of the motor 37—and begins to move downwardly along the left side of the motor, the cam follower 312 rides along the surface of edge 304 until it passes point 314 of the gate. As pivot point 230 continues to move downwardly, lever arm 236 is moved in a counterclockwise direction, and the needle bar 87 raised; rod 258 is permitted to retract to its full extent, and control link 264 moves pivot point 232 from beneath pivot point 240 towards the left in FIG. 10 so that the lines of thrust of pitman 234 is in substantial alignment with the lever. As the motor 37 continues to rotate element 220, the pivotal connection 232 will be held by control link 234 to the left of pivotal connection 240 so that the oscillating reciprocating motion of pitman 234 cannot be transmitted to the lever bar. As a result, cam follower 312 moves along the edge 316 of gate 302 between the extremes illustrated in solid and phantom lines in FIG. 10.

Quadrant gear 310 is provided with an extension 318 having a pair of lugs or stops 320 (see FIGS. 11 and 12) and, when lever 236 is held in its up position as illustrated in FIGS. 10 and 12, the lever is locked by the lugs 320 under the influence of ram 260 to prevent positively the needle bar 87 from moving downwardly.

When it is desired to re-engage lever arm 236—that is, when it is desired to begin to commence sewing again and reciprocate needle bar 87—actuator rod 258 of ram 260 is extended. As actuator rod 258 is extended, quadrant gears 306 and 310 return to the position illustrated in FIG. 9 whereby gate 302 moves in a clockwise direction. The edge 316 of gate 302 is beveled to form a ramp surface 322 on the back of the gate which depresses the detent 312 as the gate passes

thereby in order to permit the gate to move to the position illustrated in FIG. 9. As a result, lever 252 is returned to its first position; and crank 228, pitman 234 and control link 264 are returned to their positions illustrated in FIG. 9, wherein the line of thrust of the pitman is beneath lever 236 to reciprocate needle bar 87. The return to reciprocal motion of the machine can be made at any portion of the cycle; and because of the spring, biased cam detent construction can be made even when the crank arm 228 and pivot point 232 are in their uppermost position as illustrated in solid lines in FIG. 10.

For purposes of controlling the sewing machine which will be discussed in greater detail below, the sewing machine 14 contains a pneumatic stream interrupter 141 mounted on a flange wheel 140 and driven by sewing machine motor 37, a pneumatic stream bridging the gap 142 in the flange wheel 140 signals the proper position when the cylinder 260 on sewing machine 14 can be assuredly and positively engaged. The properly timed activation of cylinder 260 stops the needle in the upper position with the needle 65 in the up position. A back pressure sensor 148 (not shown) which signifies that the needle 65 is in the up position may be mounted on rod 258 of cylinder 260 in the manner as disclosed in the above-mentioned application Ser. No. 44,772.

From the foregoing, it will be apparent that a relatively simple and inexpensive sewing machine is provided for controlling the reciprocating motion of a needle bar 87 and for automatically stopping the needle bar in its uppermost position which is important for the proper operation of the welting machine.

As it is well known in the garment welt forming art, the welt opening is stitch defined by a particular stitch pattern. This stitch pattern may vary in the number of stitches but generally has a dense stitch pattern at the ends of the welt and normal stitch pattern at the center of the stitch-defined opening. FIG. 13 illustrates a typical stitch pattern employed herein in which one end of the dense pattern is indicated as 432, the other as 436 and the center stitch pattern as 434.

Further, returning now to the feed section 20, the feed piston rod 438 is attached to the feed arm or feed link 422 at piston rod pivot point 448. Feed link 422 protrudes into feed link guide block 111. In the description to follow the sewing operation in respect to the needle positioning and feeding of a work piece past the stationary needles will now be described in greater detail. The previous description of the pocket welting machine in connection with FIGS. 1 to 7 is to be understood in light of the explanation concerning FIGS. 13 to 17.

Referring now to the drawings pertaining to the feed section 20 in detail and initially to FIGS. 14 to 17, it is seen that a work feed regulator 410 incorporated in the present welting machine as shown in the drawings includes a hydraulic ram or pneumatic cylinder 412 and a speed or resistance control assembly 414 which are operatively connected through a linkage assembly further described herein to a work feed plate 11. Although in FIGS. 14 to 17 the control assembly 414 is interconnected to feed ram 412, these two elements in the combination may also be separated as illustrated in FIG. 2.

Work feed plate 11 is positioned on a pair of spaced apart rails 12, only one of which is seen in FIGS. 2 and 14 to 17 (two are shown in FIG. 3) for sliding move-

ment between a first and a second position. Linkage assembly 416 includes an oscillating control link 422 pivotally connected at 424 to the underside of work feed plate 11, between rails 12. The opposite end 426 of link 422 is pivotally mounted at 428 on a support block 430, properly positioned with respect to the sewing machine 14.

Ram 412 and control assembly 414 are operatively connected to link 422 in any of a number of relative configurations and are operative to reciprocate plate 11 along rails 12 between its first and second positions in accordance with a predetermined pattern of speeds such that the fabric supported on plate 12 is moved beneath the reciprocating needle 65 of the sewing machine at varying speeds, in order to vary the density of the stitches applied to the fabric for the same purpose as explained above and known in the art. In the preferred mode of operation, the work feed plate 11 is moved relatively slowly at the initial and final portions of its movement and more rapidly during the intermediate portion of movement so that, as shown in FIG. 13, an initial dense section of stitches 432 is formed at the beginning of the fabric in the welt defining section of the pocket opening. The increased speed of work feed plate 11 during the intermediate portion of its movement causes the stitches formed in intermediate section 434 to be more widely spaced. As work feed plate 11 is slowed down towards the end of its movement, a final dense section of stitches 436 is formed. As it is known, this configuration of stitches is preferable for sewing back pockets into slacks, since the edges of these pocket, when secured to the pants, are subjected to relatively high stresses, and the additional strength by the denser stitches is required.

Ram 412 is a double acting hydraulic or pneumatic cylinder having a piston therein (not shown) to which is connected an actuating rod 438 which is reciprocated by movement of the piston within the ram. Ram 412 is adapted to apply a relatively constant force to move rod 438, in either direction; and the latter is operatively connected to link 422 to reciprocate work feed plate 11 along rails 12. In an illustrative embodiment of the invention, seen in FIG. 14, rod 438 includes a plunger section 440 enclosed within a control cylinder 442. Plunger 440 includes an extension 444 which passes through an opening 446 in cylinder 442 and is pivotally connected to linkage 422. Plunger 440 forms part of control assembly 414 and provides variable resistance to the movement of actuator 438, and thus the piston within ram 412, in order to vary the speed at which link 422 is oscillated and thereby the speed at which work feed plate 11 is reciprocated. It is to be understood that the pivotal connections 424 and 448 illustrated in FIGS. 14 to 17 are schematic, and that these connections are constructed in a conventional manner to permit sliding motion between link 422, work feed plate 11 and extension 444 in order to accommodate the slight arcuate motion of these pivot points as illustrated in slightly more detail in FIG. 2. Such a connection is well known to mechanics in the act of reciprocating motion and need not be described herein in detail.

It is also to be understood that ram 412 may be connected to link 422 in a variety of manners. One such connection is illustrated in FIG. 15 wherein actuator rod 438 is directly connected to link 422 by a pivotal connection 450. The control assembly 414 herein re-

mains the same in structure and operation with the pivotal connection 450 being adopted to accommodate sliding movement between actuator 438 and link 422 as the pivot point 450 moves in a slightly arcuate path.

5 Similarly, as will be clear to those skilled in the art, ram 412 and control assembly 414 may be connected independently to link 422 as long as control assembly 414 is positioned as described hereinafter to resist the movement of actuator 438 from the first position of

10 work feed plate 11 to the second position thereof.

10. ~~With reference to FIG. 14 of the drawings, control mechanism 414 includes first and second ports 452 and 454 through which fluid 456 contained in a reservoir 458 is supplied to cylinder 442. Reservoir 458 is connected to cylinder 442 by conduits 460 and 462, respectively. Each of these conduits includes a restrictor 464 of conventional construction which restricts the flow of fluid from cylinder 442 to the reservoir 458.~~

Plunger 440 includes a pair of piston sections 466 and 468 which define a first chamber 470 therebetween within cylinder 442. Piston 468 defines a variable volume chamber 472 between face 474 thereof and the end wall 476 in which port 454 is formed. These pistons serve to return sequentially fluid in cylinder 442 to reservoir 458 through one or both of conduits 460 and 462, thereby controlling the speed of movement of work feed plate 11.

As mentioned before, ram 412 is a double acting ram and may be operated when it is in an initial position either at one or the other end of its stroke. In FIG. 2 the work feed plate 11 moves from right to left. Further, ram 412 and control assembly 414 may also be placed on the right hand side of lever 422, instead of left hand side as shown in FIG. 2.

35 In the first position of work feed plate 11 shown in FIG. 14, actuator rod 438 is retracted by ram 412, and plunger 440 is located in the position illustrated by FIG. 14. Chambers 470 and 472 are, in this configuration, filled with fluid supplied from reservoir 458, and
40 the pressure therein is equal because of the bleed bores 478 formed in piston 468, which bores provide inter-communication between the two chambers. In order to move work feed plate 11 from its first to its second position, ram 412 is operated to extend actuator rod 438—that is, to move the rod towards the right in FIG. 14. In the first position piston 468 closes port 452 and prevents fluid from flowing therethrough. As actuator 438 is extended, the face 474 of piston 468 increases the pressure on the fluid contained within chamber 472
45 and, since the fluid is incompressible, urges it through conduit 462 and restrictor 464 to reservoir 458. The pressure within chambers 470 and 472 remains the same because of bleed bores 478, and plunger 440 slowly moves to the right, whereby member 444 pivots
50 link 422 about pivotal mounting 428. As plunger 438 is extended, piston 468 eventually moves to the configuration illustrated in FIG. 15, wherein port 452 is open to chamber 470. At this point, since the pressure within chambers 470 and 472 is the same, the fluid contained
55 within these chambers is forced by the movement of pistons 466 and 468 through both ports 452 and 454, through conduits 460 and 462 and the restrictors 464 therein. As a result an adjustable rate of fluid flow, e.g., twice as much fluid flows from chamber 472, and thus
60 less resistance is afforded to the motion of actuator 438 and to the reciprocation of link 422. Work feed plate 11, therefore, moves faster through this portion of its
65

path of travel than during the initial portion thereof when port 452 is closed. Thus the spacing between stitches is wider during the portion of movement of work feed plate 11 when both chambers 470 and 472 are open to reservoir 458.

During the travel of the plunger from the configuration in FIG. 15 to the configuration in FIG. 16, when forced by actuator 438, the velocity of plate 418 is constant, and the wide spacing of the stitches is achieved. However, as plunger 440 continues to move toward the right past the point illustrated in FIG. 16, port 452 is closed by piston 466, and fluid is thereby prevented from flowing through this port to the reservoir. This configuration is illustrated in FIG. 17. As a result of closing port 452, continued movement of plunger 440 to the right will only force fluid through port 454 and restrictor 464 to reservoir 458, thereby increasing the resistance to movement of actuator 438 to the right, to the same level which existed during the initial portion of movement of the plunger. Accordingly, link 422 and thus work feed plate 11 are moved more slowly towards the second position of the plate, and the dense stitching section 436 is formed at the end of the stitching line.

While in the illustrative embodiment of the present invention dense stitching is provided at both ends of the stitch pattern, by closing port 452 at the beginning and end of movement of plunger 440, it is to be understood that movement of actuator 438 and thus plunger 440 may be stopped before port 452 is closed by piston 466. In this case, the dense stitching will occur only at one end of the stitch pattern. This arrangement is useful in a number of applications, as for example when sewing button holes.

When ram 412 is fully extended and actuator 438 is moved all the way to its extreme right position, as illustrated in FIG. 17, the sewing operation is completed as indicated by sensor 106, and actuator 438 is retracted in preparation for the next sewing operation.

In order to facilitate retraction of ram 412 and to assure that chamber 472 is rapidly refilled from reservoir 458 so that the speed of operation of the sewing machine is not seriously affected or constrained by the refilling rate of chamber 472, conduit 462 is provided with a bypass 480 having a check valve 482 therein. Check valve 482 prevents fluid flow through bypass 480 during movement of plunger 440 to the right. However, as the plunger is returned from the configuration, illustrated in FIG. 17, to the configuration illustrated in FIG. 14, the pressure in chamber 462 decreases, and check valve 482 opens so that fluid flows from reservoir 458 through the valve and into chamber 472 without restriction. By the time plunger 440 is fully retracted chamber 472 is filled with fluid, and the device is ready for operation again.

The description of the pneumatic circuit employing a novel fluid logic system to achieve the superior control of the novel pocket welting machine will now be discussed in further detail herein.

The wall attachment fluidic logic elements shown in FIG. 18 are those conveniently available from sources such as Corning Glass Works, Corning, N.Y.

The operational sequence of the welting machine is explained in reference to FIG. 18, wherein one of the fluidic logic control means are employed in conjunction with the back pressure machine element sensors to ensure trouble free operation. The welting machine

starts with logic element 601 which is a preferred flip-flop in a first output on-state (the O₁-ON state) thereby programming for future operation the rest of the logic elements to actuate output valves 603, 604, 607 and 609.

The programming is achieved by logic element 601 placing in a ready-to-act state logic element 613 which is a fluidic flip-flop imposing on it the desired state, i.e., causing element 613 to admit pneumatic fluid via valve 604 to the "up" side part of the double acting cylinder 67 and thus raising presser foot 16. Also, the preferred flip-flop 601 at the beginning of the sequence causes the operation of valve 602 thereby admitting pneumatic pressure to the "up" side part of the clamp cylinder 51 causing the clamps 26 to go up. Similarly, preferred flip-flop 601 causes flip-flops 613 and 620 to provide a signal to flip-flop 623 and actuate valve 607 which actuates "off" side of cylinder 260 (rod 258 retracted) which is in the sewing machine 14 stop motion device thus assuring that the sewing machine motor 37 is rotating, but the needle bar 87 is up. In the same manner but via flip-flops 613 and 626 the "forward" side of feed cylinder 412 via valve 609 is activated, i.e., to place work feed plate 11 forward. Valve 609 also operates the "forward" side of index cylinder 96 to assure that the work feed plate 11 is in the forwardmost position.

The operator then places the pocket and leg in the machine. The operator touches "clamp actuator" switch 670 which changes logic element 601 to the second output on-state (O₂-ON state) which in turn actuates output valve (OV) 601a, i.e., "down" side of cylinder 51, and de-actuates 602 thereby lowering the clamps 27.

The operator places a facing patch in the machine under the presser foot 16. As the operator touches the foot pedal 41, the "foot actuator" sensor switch provides input 671 which changes logic element 612 to the O₁-ON state which in turn changes logic element 612 to the O₃-ON state; as a result, the presser foot 16 activation via logic element 613 causes the output valve 603 to admit fluid to the "down" side of cylinder 67, for valve 604 to change state in turn provides a signal via "presser foot down" sensor 70c to the "presser foot down" input 672. Logic element 612 turns on which in turn activates logic element 615 which closes the folder blades 56. This event provides a signal via "folder blades in" sensor 58 into the "folder arms closed" input 673 which activates logic element 617. Thus the "folder blades in" back pressure sensor 58 signifies that the machine elements have moved in.

The output of logic element 617 switches logic element 626 to begin the feed, i.e., start moving the work feed plate 11 in FIG. 1 leftwardly. The output of logic element 617 goes into logic element 618 which delays the signal by ΔT_1 . This is necessary in order to let the feed cylinder 412 pressurize before activating valve 606 which activates the "on" side of cylinder 260 (actuator rod 258 extended) thereby transmitting the rotary motion from the sewing machine motor 37 (constantly rotating) and converting it to reciprocal motion of needle bar 87; otherwise without the delay the sewing machine 14 would sew in place for a few stitches while the feed cylinder 412 is pressurized. After ΔT_1 , logic element 618 turns on and provides a signal to input 676 when the notch 142 on the machine flywheel 140 (schematically represented in FIG. 11) passes be-

tween the interruptable jet sensor 141. Logic element 619 then turns on which changes the flip-flop state of logic element 620.

The input to logic element 621 is not turned off, however, until the timing capacitor 620a discharges, i.e., provides a delay. This delay (ΔT_2) allows the shifting via cylinder 260 of the reciprocating needle bar 87 at the most desirable point in the rotation of crank arm 228. After ΔT_2 delay, the O_2 output of logic element 621 turns on which provides a one-shot pulse from logic element 622, thereby changing the state of logic element 623 and turning the cylinder 260 valve 606 on (rod 258 extended). The machine then continues to feed and sew until the feed mechanism reaches the "stop sew" back pressure machine sensor 106 providing sensor input 674.

The "stop sew" sensor input 674 switches logic element 616 to the O₁-ON state and provides one-half the signal into logic element 625. The other half is provided by logic element 624 when the "synchronizer" or interruptable jet sensor 141 is interrupted providing input 676. The output of logic element 625 then changes the state of logic element 623 which retracts rod 258 of cylinder 260 via valve 607. The cylinder 260 (rod 258 retracted) input 675 (which is from a sensor mounted on the cylinder 260 in a manner as previously explained in reference to the back pressure sensing operation) then turns on logic element 627 which turns on logic element 629 and thus valve 610, and the thread pick-up fingers 72 are projected forwardly via cylinder 77. The inhibit signal into logic element 629 is delayed by logic element 628 (ΔT_3) long enough to let the fingers 72 extend fully. The output of logic element 628 then turns off logic element 629 which removes the pressure from the fingers cylinder 77 (in which a spring 77b returns piston rod 77c) and at the same time activates the index cylinder 96 valve 611.

The purpose of the index cylinder 96 is to move the table to the proper position for the end knives 134 to cut. When an input signal 677 is received from the "table back" sensor 105, a pulse is provided from logic element 630. This changes the state of logic element 632 and activates valve 612a which in turn pressurizes cylinder 127a and thus raises the end knives 134. Cylinder 127a has a spring loaded piston. When the knives 134 reach their extended position, an input signal 678 is received from the knife up sensor 139, and logic element 631 changes state which changes the state of logic element 632 and the knives 134 retract. The combination of logic element 631 and knife down sensor 139a in turn provides input signal 679 and thus turns on logic element 633 which resets logic element 601 and returns all flip-flops to their original state. This readies the machine for the next cycle. Pressing the "re-set" touch switch 600 at anytime during the cycle will reset the flip-flops to their original state.

For easy understanding of the logic circuit shown in FIG. 18, the following listing of logic elements are identified.

LOGIC ELEMENT	TYPE	FUNCTION	60	835 to 838	OR WITH LOCKING RESET	MC
601	PREFERENCED FLIP-FLOP	(memory component)		839	AND	GATE

The fluidic wall-attachment elements in the preceding table are described by their conventional terminology and are available from various sources such as Corning Glass Works, Corning, N.Y.

In reference to FIG. 19, the inputs to the fluidic circuit depicted in this figure are the same inputs as described in FIG. 18, except as indicated below. For this reason the inputs carry the same reference numbers. Further, the outputs in the form of a valve on a pneumatic fluid line (shop air) are similarly the same and hence carry the same reference numbers. In respect to the outputs in FIG. 19, the only difference from the circuit shown in FIG. 18 is in the counter 682 which is a pneumatic to electric interface operating an electric counter (not shown) to record the total number of machine cycles.

In reference to the transverse impact modulator (TIM) fluidic devices which are NOR gates and from which the fluidic circuit depicted in FIG. 19 is constructed in combination with orifice restrictors, delay means, and fluidic diodes, these fluidic devices, i.e., transverse impact modulators, delay means, orifice restrictors and diodes, are available on the market such as from Johnson Service Company, Milwaukee, Wis. 53201.

In brief, from the TIM NOR gate various combinations may be obtained as illustrated in FIG. 19 and illustratively listed herein below.

		TYPE	FUNCTION
40	LOGIC ELEMENTS OR CIRCUIT ELEMENTS 801 and 802	OR	MEMORY COMPONENT (MC)

Inasmuch as the operating sequence of the welting machine when controlled by the circuit described in FIG. 19 follows the same sequence as previously described in respect to FIG. 18, the differences reside merely in the arrangement of the fluidic circuit elements and the additional functions provided with this circuit. Briefly, the controlled welting operation will now be described.

The transverse impact modulators (TIM) 803 and 804 constitute the preferred flip-flop as listed above. Accordingly, when the fluid in the fluidic circuit (such as air used with the circuit in FIG. 19) is turned on, TIM 803 is on; and as this memory component is tied to all other bistable flip-flops either directly or through another flip-flop, these flip-flops will be started in the preferred condition, i.e., with no input to the flip-flops 813-814, 827-828, 829-830 and 841-842, these flip-flops will have an indeterminate start-up condition, but with an input the proper "start" condition is imposed on these (when 803 is on).

As a consequence of the foregoing, the pocket welting machine at the beginning of its cycle starts with output valves 602, 604 and 607, and 609, admitting pneumatic fluid to the "up" side of clamp cylinder 51 and presser foot cylinder 67, "off" side of the stop motion device cylinder 260 (rod 258 retracted) and assuring that feed plate 11 is forward (in FIG. 2 cylinder 412 rod 438 is retracted; however, if feed cylinder pulls instead of pushes as in FIG. 2, the proper condition can be imposed by the proper placement of the valve 609 on the "work" side of the cylinder). As index cylinder (shown in FIG. 4) is tied in with the feed plate at the beginning of cycle via valve 609, cylinder 96 retracts rod 97 and assures that feed plate 11 is in its forwardmost position (in FIG. 2 the index cylinder 9 is placed in reverse from that in FIG. 4, hence rod 97 would be extended under that configuration).

After the operator has placed a pants pocket and a pants leg in the machine, he steps on the foot pedal 41 once which changes the state of flip-flop 803-804, i.e., whereby 803 is off and 804 is on.

As a result, flip-flop 803-804 changes in turn the state of the OR/NOR combination 805 and 806 as a consequence of which output valve 601a is actuated and output valve 602 is deactivated thereby admitting pneumatic fluid to "down" side of cylinder 51 lowering the pant clamps 27. Next, the operator places a facing in the machine. As indicated in the list above, TIMs 807 to 812 form a binary counter; this counter is activated upon occurrence of two events—a first depression of foot pedal 41 and a second depression of foot pedal 41. Thus when foot pedal 41 is stepped on a second time, a second signal is furnished from the binary counter 807 to 812 to flip-flop 813-814 thereby turning 813 off and 814 on and it activates output valve 603 and the "down" side of cylinder 67. Thereafter, the pocket welting machine performs its work cycle without further operator assistance as follows. When the presser foot 16 drops, a signal is received from the "foot down" sensor 70c as input 672 which provides a signal to 817 (AND - GATE) and closes folder arms 56 (by activating normally spring loaded, "when open," cylinders 57). As a result, sensor 58 provides "folder arms closed" input 673, which provides a signal to 818 and 819. As 827-828 flip-flop is on in one state, this flip-flop together with 818 and 819 form the AND gate

which turns on the one shot multivibrator 820 to 823 (as explained below) as well as flip-flop 829-830 and thus opens the "feed back" output valve 608 and turns off "feed-forward" output valve 609. After a time delay T_1 in capacitor or fluidic delay 846a to assure that feed cylinder 412 is pressurized before sewing starts, a pulse is provided to AND gate 824 which changes the state of OR/NOR gate 825-826 and causes output valve 606 to go on (i.e., stop motion device disengaged, rod 258 of cylinder 260 extended, sewing machine sewing) and output valve 607 to go off (stop motion device engaged, needle bar 87 not reciprocating). No intermittent feed is provided as the flexibility of the needles and sewing rate allow the sewing of the fabric layers without intermittent motion. However, an intermittent feed may be provided. After the machine has sewn for a predetermined distance, the "stop sew" sensor 106 is covered providing sensor input 674 to flip-flop 827-828 which again changes the state of 819 (which is an AND gate in combination with 818 and 827-829) and in turn, through logic elements 820 to 826 described above, engages the stop motion device, i.e., retracts cylinder rod 258.

After a time delay of T_2 in fluidic delay 846b which assures that cylinder 260 rod 258 is retracted, the AND gate 831 provides a signal to gates 834 and 839 and thus changes their state which activates output valve 610 extending the thread fingers 62. The delay T_3 introduced in the one shot multivibrator 832, 833 and 834 by fluidic delay 846c, in combination, provides a pulse to gate 834, and the output valve 610 is turned off, and the thread fingers 72 retract (spring 77b is reTRACTING fingers).

Time delay T_4 obtained by capacitor 846d, which in combination with fluidic check valve or diode 845 is equivalent to a R/C time delay, assures that thread fingers 62 have operated, and when this delay has elapsed NOR gate 840 is turned on which places indexes table 11 above the end knives 134 by activating valve 611. At the same time flip-flop 841-842 changes state as does logic element 817 thereby causing the opening of folder arms (output valve 605 is deactivated, cylinder 57 is spring returned). When an input signal 677 is received from the "table back" sensor 105, logic elements 835 to 838 change state and cylinder 127a is extended by activating valve 612a. Logic elements 835 to 838 in combination act as OR with locking reset (disregarding the other functions which are imposed on it), i.e., with no inputs, output(s) is off; input at 677 turns output at 836 on; input at 678 turns output at 836 off; output at 836 will remain off until input 677 is removed and reapplied. When "knife down" 139a provides input signal 679, NOR gate 843 and two-input AND gate 844 change state, which provides a reset signal to preferred flip-flop 803-804 and the other flip-flops as discussed above and thus cause the machine to be ready for another work cycle. Input 680 which is not found in FIG. 18 is a toggle switch which inhibits the operation of AND gate 817 thereby stopping the welting machine from continuing its cycle. It is used when the operator wants to rethread the sewing machine.

Input 681 is a toggle switch and is labeled in FIG. 19 as a "repair switch." It inhibits the operation of the knife cylinder 127a in case a thread breaks during a sewing cycle and the operation wishes to repair the welt facing. In line with the above discussion, pocket clamp 21 may be activated from an input which precedes

"clamps down" (precedes 601a output) or simultaneously therewith; clamp 21 may be deactivated when "end knife down" sensor furnishes an input.

In respect to input 683 which is labeled as a clutch override in FIG. 19, in the "off" position the stop motion device is engaged and needle bar 87 does not move. In the "on" position, input 683 allows the operation of the needle bar so that the needle bar 87 may be adjusted for timing and for proper functioning of the needle and looper in the stitch formation. Normally input 683 is kept in the "run" position.

In FIGS. 18 and 19 the logic elements have been drawn without their operating fluid inputs as these would otherwise unduly complicate the presentation of the logic circuit. The operating fluid is supplied from a common manifold generally at 3 psi. The mounting of these elements may be accomplished in the conventional manner.

The above-described fluidic circuit allows the proper operation, control and monitoring of the pocket welt-forming machine. As a result of the combination of the novel fluidic circuits with the mechanical elements comprising a novel combination of elements, an improved pocket welt-forming machine has been described which is a contribution in the art of producing garments.

What is claimed is:

1. In a garment welt forming machine, the combination comprising: a sewing machine; feed means extending transversely of said sewing machine; means for moving said feed means between a first and a second feed position with respect to said sewing machine; means for clamping a first and second work piece in superimposed relation onto said feed means and being operatively interconnected with said feed means; means for holding a third work piece in superimposed relation with respect to said first and second work pieces, said holding means being operatively interconnected with said feed means and said means for clamping; means for folding said third work piece about said holding means; means for initiating sewing of said sewing machine for sewing said second and third work piece to said first work piece along a stitching path as said feed means is moved between said first and second feed positions; means for cutting said first, second and third work pieces along a cutting path adjacent to said stitching path, said cutting means being operatively interconnected with said sewing machine and said feed means between said first and second feed positions; means for indexing said feed means between said second feed position and a third index position; means at said third index position for end cutting said first, second and third work pieces at the ends of said cutting path; said end cutting means being operatively interconnected with said means for indexing said feed means.

2. The machine as defined in claim 1 and including means for ejecting the sewn together work pieces after cutting by said end cutting means.

3. The machine as defined in claim 1 and including means for controlling the operation of said machine.

4. The machine as defined in claim 3 and including fluidic control means for controlling the sequence of operation of said machine.

5. The machine as defined in claim 3 and including fluidic control means for automatic cycling of the sequence of operation of said machine.

6. In a welt forming machine, the combination comprising: a sewing machine including a needle bar and a stop motion means for the needle bar; feed means for feeding a work piece for said sewing machine including means for varying the rate of feeding of said feed means independently of a rate of sewing, said feed means feedingly urging a work piece transversely to said sewing machine between a first feed and a second feed position whereby said sewing machine forms a stitching path along the work piece; means for clamping a first and a second work piece in superimposed relation onto said feed means and being operatively interconnected with said feed means; means for holding a third work piece in superimposed relation with respect to said first and second work pieces said holding means being operatively interconnected with said feed means and said means for clamping and transversely depending from said sewing machine; means for folding said third work piece about said holding means, said folding means being operatively interconnected with said feed means and said clamping means and articulantly interconnected with said clamping means; means for cutting said first, second and third work pieces along a cutting path adjacent to said stitching path, said cutting means being operatively interconnected with said needle bar of said sewing machine and said feed means between said first and second feed position; means for engaging said stop motion means; means for engaging an upper thread of said sewing machine upon completion of sewing of said first and second and third work pieces; means for cutting said upper thread operatively interconnected with said means for engaging said upper thread; means for indexing said feed means between said second feed position and a third index position; means at said third index position for end cutting said first second and third work pieces at the ends of said cutting path, said end cutting means being operatively interconnected with said means for indexing said feed means.

7. The machine as defined in claim 6 and including control means for controlling the sequence of operation of said machine.

8. The machine as defined in claim 7 and wherein the control means are fluidic control means.

9. The machine as defined in claim 8 including back pressure sensor means for detecting the presence of said feed means in said index position, said fluidic control means being responsive to said back pressure sensor means for automatically controlling operation of said machine.

10. The machine as defined in claim 9 and wherein wall attachment fluidic control means are said fluidic control means.

11. The machine as defined in claim 9 and wherein impact modulators are said fluidic control means.

12. In a garment welt forming machine, the combination comprising: a sewing machine; feed means extending transversely of said sewing machine; means for moving said feed means between a first and a second feed position; means for clamping a work piece onto said feed means and being operatively interconnected with said feed means; means for holding a welt defining work piece in superimposed relation on said work piece and being operatively interconnected with said feed means and said means for clamping; means for folding said welt defining work piece; means for initiating sewing of said sewing machine for sewing said welt defining

work piece to said work piece along a stitching path as said feed means is moved between said first and second feed positions; means for cutting said work pieces along a cutting path adjacent to said stitching path, said cutting means being operatively interconnected with said sewing machine and said feed means between said first and second feed positions; means for indexing said feed means between said second feed position and a third index position; means at said third position for end cutting said work pieces at the ends of said cutting path, said end cutting means being operatively interconnected with said means for indexing said feed means; means for further indexing to a fourth index position said work feed plate; means for inverting said welt defining path; and means for returning said feed means to said feed position.

13. The machine as defined in claim 12 and wherein said feed means for said sewing machine comprise a work feed plate reciprocating between said first and said second feed positions at varying speeds in a predetermined sequence; said means for moving said feed means comprises means operably connected to said work feed plate for applying a uniform force to said feed plate to move the feed plate between said first and said second positions; and means for variably resisting movement of said feed plate in accordance with said predetermined sequence to vary the speed of movement of said feed plate from said first to said second position, said resisting means including a hydraulic control cylinder having at least two ports therein, a fluid reservoir in communication with said cylinder through said ports, and plunger means in said cylinder operatively connected to said feed plate and cooperating with fluid in said cylinder for resisting movement of said feed plate by said force applying means and for sequentially returning fluid in said reservoir from said cylinder as said feed plate is moved from its first to its second position by said force applying means, initially through only one of said ports, then through both ports, and finally through only said one port whereby movement of said feed plate is variably resisted and said feed plate is moved faster between said first and second positions of said feed plate when fluid is returned to said reservoir through both of said ports than when fluid is returned to said reservoir through only said one port during the initial and final portions of movement of said feed plate.

14. The feed means as defined in claim 13 wherein said reservoir is connected to said cylinder ports by independent conduit means, and said conduit means include restrictions therein resisting fluid flow therethrough.

15. The feed means as defined in claim 13 including check valve means interconnecting said reservoir to said cylinder for permitting free flow of fluid therethrough from said reservoir to said cylinder as said feed plate is returned by said force applying means from its second to its first position.

16. The feed means defined in claim 15 wherein said plunger comprises a pair of spaced, operatively interconnected pistons defining a first fluid chamber therebetween in said cylinder, said plunger being moved with said feed plate by the force applying means from a first to a second position corresponding to the first and second positions of said feed plate to selectively close said one port at the initial and final portions of movement of said feed plate.

17. The machine as defined in claim 12 and including means for ejecting the sewn together work pieces after cutting by said end cutting means.

18. The machine as defined in claim 12 and including a stop motion means for said sewing machine.

19. The machine as defined in claim 12 and including means for controlling the sequence of operation of the machine.

20. The machine as defined in claim 19 and including fluidic control means for controlling the sequence of operation of the machine.

21. The machine as defined in claim 19 and including fluidic control means for automatic cycling of the sequence of operation of the machine.

22. In a welt forming machine, the combination comprising: a sewing machine including a looper, a needle bar and a stop motion means for sewing machine needle bar; feed means for feeding a work piece for said sewing machine including means for varying the rate of feeding of said feed means independently of a rate of sewing, said feed means feedingly urging a work piece transversely to said sewing machine between a first feed and a second feed position whereby said sewing machine forms a stitching path along the work piece; means for clamping a work piece onto said feed means and operatively interconnected with said feed means; means for holding a welt-defining work piece in superimposed relation with respect to the first mentioned work piece, said holding means being operatively interconnected with said feed means and said means for clamping, said holding means transversely depending from said sewing machine; means for folding said welt-defining work piece operatively interconnected with said feed means and said clamping means and articulately interconnected with said clamping means; means for cutting said work pieces along a cutting path adjacent to said stitching path, said cutting means being operatively interconnected with said sewing machine and said feed means between said first and second feed position; means for engaging and disengaging said stop motion means; means for engaging an upper thread of said sewing machine upon completion of sewing of said work pieces; means for cutting said upper thread operatively interconnected with said means for engaging said upper thread; means for indexing said feed means between said second position and a third index position; means at said third index position for end cutting said work pieces at the ends of said cutting path, said end cutting means being operatively interconnected with said means for indexing said feed means.

23. The machine as defined in claim 22 wherein said needle bar is mounted in said sewing machine for movement between upper and lower positions with respect to said looper and wherein said stop motion means include a first lever pivotally mounted in said sewing machine and pivotally connected to said needle bar for transmitting reciprocating motion thereto, rotary drive means, a crank pivotally connected at one end to said rotary drive means, and a pitman pivotally connected between said crank and said first lever whereby rotary motion of said drive means is transmitted through said crank, pitman and lever to reciprocate said needle bar between said upper and lower positions, second lever means pivotally mounted in said sewing machine, means for moving said second lever between first and second positions and a control link pivotally connected at one end to said second lever and at its

other end to said crank arm at the pivotal connection between said crank arm and said pitman, said second lever and said control link cooperating in the first position of said second lever to hold said pitman in a position substantially perpendicular to said first lever whereby the motion of said rotary drive means is transmitted to said first lever to reciprocate said needle bar, and in the second position of said second lever to hold said pitman in a position substantially in alignment with said first lever whereby said pitman idles under the influence of said drive means without transmitting motion to said first lever.

24. The machine as defined in claim 22 and wherein said feed means include a work feed plate for reciprocating the same between first and second positions at varying speeds in a predetermined sequence comprising means operably connected to said work feed plate for applying in a uniform force to said plate to move the plate between said first and said second positions and means for variably resisting movement of said plate in accordance with said predetermined sequence to vary the speed of movement of said plate from said first to said second position, said resisting means including a hydraulic control cylinder having at least two ports therein, a fluid reservoir in communication with said cylinder through said ports, and plunger means in said cylinder operatively connected to said plate and cooperating with fluid in said cylinder for resisting movement of said plate by said force applying means and for sequentially returning fluid to said reservoir from said cylinder as said plate is moved from its first to its second position by said force applying means, initially through only one of said ports, then through both ports, whereby movement of said plate is variably resisted and said plate is moved faster between said first and second positions when fluid is returned to said reservoir through both of said ports than when fluid is returned to said reservoir through only said one port.

25. The machine as defined in claim 22 and including control means for controlling the sequence of operation of said machine.

26. The machine as defined in claim 25 and wherein the control means are fluidic control means.

27. The machine as defined in claim 25 including back pressure sensor means for detecting the presence of said feed means in said index position, said fluidic control means being responsive to said back pressure sensor means for automatically controlling operation of said machine.

28. The machine as defined in claim 25 and wherein the control means are wall attachment fluidic control means and back pressure sensor means.

29. The machine as defined in claim 25 and wherein impact modulators are said control means.

30. In a welt forming machine the combination comprising: a sewing machine including a motor therefor; a stop motion means for a sewing machine needle bar operatively interconnected with said motor; means for engaging and means for disengaging said stop motion means; means for synchronizing said means for engaging with said stop motion means for positioning said needle bar in an up-position in an inoperative sewing mode of said welt forming machine; feed means for feeding a work piece to said sewing machine including means for varying the rate of feeding of said feed means independently of a rate of sewing of said machine, said feed means being operatively interconnected with

means for synchronizing said means for disengaging said stop motion means and means for sensing completion of sewing; means for clamping a first and a second work piece in superimposed relation onto said feed means, including means for initiating said clamping; means for holding a third work piece in superimposed relation with respect to said first and second work pieces, said holding means being operatively interconnected with said feed means and said means for clamping, said holding means including means for sensing an operative position in engagement with said work piece and an inoperative position, said holding means depending from said sewing machine longitudinally with respect to said feed means and transversely from said sewing machine; means for folding said third work piece operatively interconnected with clamping means and means sensing said operative position of said means for holding said third work piece; means for initiating said means for disengaging said stop motion means and said means for synchronizing whereby said sewing machine is placed in an operative mode to sew said work pieces together along a stitching path; means for cutting said work pieces along a cutting path adjacent to said stitching path, said cutting means being operatively interconnected with said sewing machine and cammingly interconnected with said feed means during a movement thereof between first and second feed positions; means for sensing completion of sewing; means for engaging an upper thread of said sewing machine upon completion of sewing of said work pieces, said upper thread engaging means being operatively interconnected with (i) said means for sensing completion of sewing, (ii) said stop motion means for said sewing machine needle bar and (iii) said means for synchronizing said means for engaging said stop motion means; means for cutting said upper thread operatively interconnected with said means for engaging said upper thread and said feed means; means for indexing said feed means from said second position to a third position and being operatively interconnected with said means for engaging said upper thread and said means for sensing completion of sewing; means for end cutting said work pieces at the ends of said cutting path, said end cutting means being operatively interconnected with said means for indexing of said feed means, said indexing means including means for sensing a completion of an indexing of said feed means; and means for returning said feed means from said third position to said first feed position operatively interconnected with means for sensing a completion of operation of said means for end cutting of said work pieces.

31. The machine as defined in claim 30 and including means for ejecting the sewn together work pieces after cutting by said end cutting means.

32. The machine as defined in claim 30 and including means for securing said first work piece operatively interconnected with means for returning said feed means.

33. The machine as defined in claim 30 and wherein the means for returning said feed means include means for placing said weltting machine in a ready-to-operate condition.

34. The machine as defined in claim 33 and wherein the means for placing said weltting machine in a ready-to-operate condition includes means for raising said clamps, means for raising said means for holding said third work piece, means for engaging said stop motion

means for said sewing machine, and means for returning said index means for indexing said feed means.

35. In a welt forming machine the combination comprising: a sewing machine; a needle bar, a looper, and a drive means therefor; a stop motion means for said needle bar; means for engaging and disengaging said needle bar and said looper and said stop motion means for said sewing machine needle bar including means for synchronizing said means for engaging said needle bar and said looper and said stop motion means for positioning said needle bar in an up-position in an inoperative sewing mode of said sewing machine; feed means for feeding a work piece to said sewing machine including means for varying the rate of feeding of said feed means independently of a rate of sewing of said sewing machine; means for sensing completion of sewing, said feed means being operatively interconnected with said means for synchronizing said means for engaging and disengaging said needle bar and said looper and said stop motion device and said means for sensing completion of sewing; means for clamping a work piece onto said feed means, including means for initiating said clamping; means for holding a welt-defining work piece superimposed on said first mentioned work piece, said holding means being operatively interconnected with said feed means and said means for clamping, said holding means including means for sensing an operative position and an inoperative position, said holding means depending from said sewing machine longitudinally with said feed means and transversely from said sewing machine; means for folding said welt-defining work piece operatively interconnected with clamping means and means sensing said holding position of said means for holding said welt-defining work piece; means for initiating said means for disengaging said needle bar and said looper and said means for synchronizing said stop motion means whereby said sewing machine is placed in an operative mode for sewing said work pieces together along a stitching path; means for cutting said work pieces along a cutting path adjacent to said stitching path being operatively interconnected with said sewing machine and cammingly interconnected with said feed means between first and second feed positions thereof; means for engaging an upper thread of said sewing machine upon completion of sewing of said work pieces operatively interconnected with (i) said means for sensing completion of sewing, (ii) said stop motion means for said sewing machine needle bar and (iii) said means for synchronizing said means for engaging said needle bar and looper and said stop motion means; means for cutting said upper thread operatively interconnected with said means for engaging upper thread and feed means; means for indexing said feed means from said second position to a third index position, said indexing means being operatively interconnected with said means for engaging said upper thread and said means for sensing completion of sewing; means for end cutting said work pieces at the ends of said cutting path and being operatively interconnected with said means for indexing of said feed means; said indexing means including means for sensing a completion of an indexing of said feed means; and means for returning said feed means to said first feed position; and operatively interconnected with said returning means for sensing a completion of operation of said means for end cutting of said work pieces.

36. The welt forming machine as defined in claim 35 and wherein the feed means for feeding a work piece to said sewing machine including the means for varying the feed means independently of a rate of sewing of said machine comprises: a work feed plate for supporting and moving said work piece to be sewn beneath the needle bar of said sewing machine and wherein the feed plate is mounted for reciprocal movement between first and second positions at varying speeds and in a predetermined sequence for varying the spacing between stitches sewn into the work piece, means for reciprocating the plate at varying speeds comprising a ram operatively connected to said feed plate for applying a uniform force thereto to move the feed plate between said first to said second positions and means for variably resisting movement of said feed plate in accordance with said predetermined sequence to vary the speed of movement of said feed plate from said first to said second position and thereby vary said stitch spacing, including a hydraulic control cylinder having at least first and second ports therein, a plunger in said cylinder operatively connected to said work feed plate for movement therewith under the influence of said ram between first and second positions corresponding respectively to the first and second positions of said feed plate, said plunger having first and second spaced operatively interconnected pistons defining a first fluid chamber in said cylinder, a reservoir, independent conduit means respectively connecting said reservoir to said ports, said first ports being located for communication with said first chamber and said second port being located for communication with a second fluid chamber defined by said first piston and one end of said cylinder, said first piston having at least one bleed bore therein to provide communication between said first and second chambers for equalizing fluid pressure therein and said pistons cooperating with fluid in said cylinder for resisting movement of said feed plate by said ram in accordance with said predetermined sequence, said first piston closing said first port in the first position thereof and forcing fluid in said second chamber through said second port during initial movement of said plunger from its first to its second position and opening said first port to said first chamber after said initial movement, movement of said second piston thereafter forcing fluid in said second chamber through said first port to said reservoir, while movement of said first piston continues to force fluid to said reservoir through said port, thereby decreasing the resistance to movement of said plate, said second piston thereafter being moved into position to close said first port as said plunger approaches its second position while said first piston continues to force fluid to said reservoir through said second port, whereby the speed of movement of said feed plate is sequentially varied to provide relatively small spacing between stitches at the beginning and ends of movement of said plate from its first to its second position and wider spacing between stitches at the intermediate portion of said movement.

37. The feed means for said sewing machine as defined in claim 36 and wherein said conduits have fluid flow restrictors therein.

38. The feed means for said sewing machine as defined in claim 37 and wherein said ram is a double acting ram adapted to return said feed plate from its second to its first position.

39. The feed means for said sewing machine as defined in claim 38 and wherein one of said conduits includes a conduit portion by passing the flow restrictor therein and a check valve in said bypass permitting free return of fluid in said reservoir to said cylinder as said feed plate and plunger are returned from their second to their first positions.

40. The welt forming machine as defined in claim 35 wherein said needle bar is mounted in said sewing machine for movement between upper and lower positions with respect to said looper, a first lever pivotally mounted in said sewing machine and pivotally connected to said needle bar for transmitting reciprocating motion thereto, rotary drive means, a crank pivotally connected at one end to said rotary drive means, and a pitman pivotally connected between said crank and said first lever whereby rotary motion of said drive means is transmitted through said crank, pitman and lever to reciprocate said needle bar between said upper and lower positions, second lever means pivotally mounted in said sewing machine, means for moving said second lever between first and second positions and a control link pivotally connected at one end to said second lever and at its other end to said crank arm at the pivotal connection between said crank arm and said pitman, said second lever and said control link cooperating in the first position of said second lever to hold said pitman in a position substantially perpendicular to said first lever whereby the motion of said rotary drive means is transmitted to said first lever to reciprocate said needle bar, and in the second position of said second lever to hold said pitman in a position substantially in alignment with said first lever whereby said pitman idles under the influence of said drive means without transmitting motion to said first lever.

41. The welt forming machine as defined in claim 35 including gate means for preventing movement of said second lever from said first to said second position thereof until said crank arm, pitman and first lever has achieved a relative configuration due to the rotational motion of said drive means corresponding to the raised position of said needle bar.

42. The welt forming machine as defined in claim 41 and wherein said gate means comprises a cam plate positioned in path along which said point of connection between the crank arm and the pitman travels as said second lever moves between its first and second positions.

43. The welt forming machine as defined in claim 42 including means operably connected between said first lever and said looper for transmitting motion therebetween to oscillate said looper.

44. The welt forming machine as defined in claim 43 including stop means defining the limits of movement of said second lever between said first and second positions.

45. The welt forming machine as defined in claim 43 and wherein said cam plate is pivotally mounted in said machine and means operably connected between said second lever and said cam plate for moving said cam plate into said path of travel as said second lever is moved to its second position.

46. The welt forming machine as defined in claim 45 and wherein said cam plate moving means comprises a meshed pair of quadrant gears respectively connected to said cam plate and said second lever.

47. The welt forming machine as defined in claim 46 including a spring biased cam follower located at the pivotal connection between said crank and said pitman, said cam plate having a first cam surface adapted to be engaged by said cam follower to prevent movement of said second lever from said first to said second position thereof until said crank arm, pitman and first lever arm have achieved a relative configuration due to the rotational motion of said drive means corresponding to the raised position of said needle bar, and a second cam surface for moving said cam follower against its spring bias as said second lever is moved from its second to its first position to permit said cam follower and cam plate to move relative to each other as said cam follower is moved out of said path of travel by said quadrant gears.

48. The machine as defined in claim 35 and wherein the means for returning said feed means include means for placing said welting machine in a ready-to-operate condition.

49. The machine as defined in claim 35 and wherein the means for placing said welting machine in a ready-to-operate condition includes means for raising said clamps, means for raising said means for holding said welt-defining work piece, means for engaging said needle bar and said loopers and said stop for synchronizing means, and means for returning said index means for indexing said feed means. said needle

50. In a welt forming machine for garments and the like, the combination comprising: a sewing machine including a needle bar, a looper, and drive means therefor; a stop motion means for said sewing machine needle bar; means for engaging and means for disengaging said stop motion means; means for synchronizing said means for engaging said stop motion means and said stop motion means for positioning said needle bar in an up-position in an inoperative sewing mode of said sewing machine; means for synchronizing said stop motion means and said means for disengaging said stop motion means for placing in an operative sewing mode said sewing machine; work feed plate for feeding a work piece to said sewing machine, whereby said sewing machine sews the work piece along a stitch path, said work feed plate including a cam land, a pair of spaced apart rails athwart of said sewing machine for guiding said work plate, a power stroking cylinder for reciprocating said work feed plate, restraint means for restraining said power stroke of said power stroking cylinder in a predetermined manner for varying the rate of feeding of said work feed plate independently of a rate of sewing of said sewing machine; means for rendering inoperative said restraint means during an inoperative mode of sewing by said sewing machine; an index cylinder for indexing of said work feed plate after completion of said sewing including means for interconnecting said index cylinder to said feed plate in a predetermined position in an operative mode of sewing by said sewing machine; a pair of clamps and a pivot point for said clamps affixed to said work feed plate for reciprocally upwardly and downwardly articulating said clamps; a pair of folder arms interiorly to said clamps and supportingly and articulately interconnected to said clamps; a cylinder for each of said folder arms for inwardly and outwardly reciprocating each of said folder arms; a presser foot for said sewing machine athwartingly and operatively interconnected with said sewing machine; a pair of knives for each for cutting an upper thread of said sewing machine; a pair of thread pickup

60

fingers longitudinally interconnected with said presser foot including a cylinder for said pickup fingers for extending said pickup fingers for engagement with said upper thread of said sewing machine and for cuttingly holding said thread against said knife upon completion of said operative mode of sewing by said sewing machine; a cylinder for said presser foot for upwardly and downwardly reciprocating said presser foot for including said thread pickup fingers; a center cut knife operatively pivotingly interconnected to said sewing machine needle bar including a knife cam follower integral with said center cut knife and a spring for said center cut knife, a cam for said center cut knife articulately affixed to said sewing machine; a cam follower interconnected to said cam land on said work feed plate and said cam for said center cut knife for articulately positioning in a predetermined manner said cam for said center cut knife whereby said center cut knife cuts said work piece along a cutting path adjacent to said stitch path during sewing by said machine; a pair of end cut 20

knives including a bar for holding each of said end cut knives spacedly and predeterminedly apart and a cylinder for urging said bar upwardly operatively interconnected with said work feed plate, said index cylinder, said clamp, and said folder arms to cut said work piece at the ends of said cutting path upon completion of sewing by said machine.

5 51. The welting machine as defined in claim 50 and wherein said work feed plate includes a flexible spring, 10 a necked down portion on said spring, a holder for said spring, a cylinder attached to said spring for operative engagement of said spring, said holder of said spring and said work feed plate, whereby a work piece is placed under said spring when said necked down portion of said spring is in said holder and said work piece is held against said work feed plate when said cylinder removes said necked down portion of said spring from said holder.
